UNITED STATES PATENT OFFICE.

JAMES J. HINDE, OF SANDUSKY, OHIO, ASSIGNOR TO THE HINDE & DAUCH PAPER COMPANY,
OF SANDUSKY, OHIO, A CORPORATION OF OHIO.

APPARATUS FOR FORMING MULTIPLY MATERIAL.

No. 905,076.

Specification of Letters Patent.

Patented Nov. 24, 1908.

Application filed November 25, 1907. Serial No. 403,683.

To all whom it may concern:

Be it known that I, JAMES J. HINDE, a citizen of the United States of America, residing at Sandusky, in the county of Erie and State of Ohio, have invented certain new and useful improvements in Apparatus for Forming Multiply Material, of which the following is a specification, reference being had therein to the accompanying drawings.

10 The invention relates generally to an apparatus for producing multiply material in which the layers or plies are cemented together into sheet form, as in what is generally termed double-faced corrugated paper strawboard and the like.

15 The invention consists in the novel construction of the apparatus, in the peculiar arrangement and combination of its parts, and in various details of construction, as 20 more fully hereinafter set forth.

In the drawings,—Figure 1 is a side elevation of the apparatus; Fig. 2 is a plan view; Figs. 3, 4 and 5 are detached sectional views, in elevation and plan, of the pressing mechanism; Figs. 6 and 7 are cross sections in different planes through the feed and cutting mechanism; Fig. 8 is a longitudinal section through the feed mechanism; Fig. 9 is a similar section taken centrally through the 25 framework; Fig. 10 is a plan view, partly in section, showing the drive mechanism; Fig. 11 is a view in elevation of parts of the timing mechanism; Fig. 12 is a sectional view of the driving means for the feed mechanism; and Fig. 13 is a view in elevation of 30 parts of the timing mechanism.

For the purpose of describing the invention, the apparatus has been shown and will be hereinafter described as designed for producing double-faced strawboard, and for this purpose its general construction consists of mechanism for feeding superimposed layers of strawboard, in means for applying adhesive material intermediate the layers, mechanism for applying fluid pressure to the coated layers for the purpose of cementing them together, and in a cut-off mechanism, preferably a single cutter,—for severing the formed multiply sheet into the desired 45 lengths. The mechanism preferably employed for applying fluid pressure to the strawboard is a pneumatic press, but it will be obvious from the following description that any means may be employed that will 50 permit a fluid pressure to be applied,—the

particular advantages of the use of this form of pressure being more fully hereinafter set forth.

The press comprises generally a bed 1 and a platen 2 having a yielding or flexible pressing surface 3. As shown, the platen is in the form of a closed casing 4, the pressing surface 3 of which is a flexible diaphragm forming the casing bottom, and beneath which and the bed the plies of material are 60 adapted to pass. Communicating with the interior of the casing described is an air conduit 5, through which air from a suitable source of supply, as a blower 6, is forced within the casing for the purpose of depressing the diaphragm. A valve 7 controls the admission of air within the press, and, consequently, the operation of the latter, and this valve (as hereinafter set forth) is intermittently operated alternately with the feed 65 70 mechanism.

Any form of controlling means may be used for the air conduit, but I have preferably shown a valve of the slide type, having a sliding engagement with the air conduit 80 and supported upon an upright exhaust pipe 8 open at its top and having communication laterally through a pipe 9 with the air pipe 5. The slide valve is apertured, as at 10, and the parts are so arranged and proportioned that, as the valve is withdrawn from the position indicated in full lines in Fig. 3 to permit the entry of air within the press, the exhaust pipe 10 will be closed so as to maintain the desired pressure upon the multiply material within the press, and, upon a reversal of the valve, the air supply will be 85 cut off and the pressure within the press relieved by the discharge of the air through the exhaust. 90

To expedite the cementing of the layers of strawboard, hot air is used in the operation of pressing, and a drier 11 is also applied in operative relation to the bed 1, so that when the material passes through the 100 press it is sufficiently set to permit of its being cut into sheets of the desired length. 95

I have shown in the drawings as the preferable form of drier a system of steam piping 12, and have constructed the bed with a 105 chamber 13 therein to receive the pipes, the latter being mounted upon suitable supports 14. The ends of the pipes of the system, as shown in Fig. 5, project through and beyond the bed 1, and are adapted to connect with 110

conduits leading to a suitable source of supply.

The strawboard is drawn through the press by feed rollers (hereinafter described), 5 and is adapted to be coated with adhesive material just prior to its entry within the press. I have shown, as the preferable form of means for applying the adhesive, a bath 15, with a roll 16 mounted to dip within the 10 bath during its rotation, a suitable support, as 17, on which the parts are mounted, and reels 18 and 19 for the strawboard. Upon the reel 18 a quantity of single-faced strawboard is shown, consisting of a plain layer 15 of paper and a corrugated layer, the material passing beneath a roller 20 before passing over the adhesive roll 16, the roll 20 serving to hold the strawboard in contact with the roll 16 so as to receive the proper 20 amount of adhesive. Upon the reel 19 is a continuous sheet of plane strawboard, which is adapted to pass over a roll 21 and beneath the single-faced strawboard prior to entering the press.

25 The feed mechanism, as previously set forth, is in the form of corrugated feed rolls,—three sets, 25, 26 and 27, being employed,—mounted in standards 28 upon a suitable framework 29. These rolls are 30 operated by a drive mechanism, consisting of a driven sprocket 30 loosely mounted upon a shaft 31 journaled in bearings in the framework 29, a drive connection between the rolls and the sprocket comprising a suitable gear train 32 between the rolls and a gear 33 fixed upon the shaft 31, and a clutch 34 forming a drive connection between the gear 33 and the sprocket.

The feed is adapted to be operated intermittently to allow of the action of the press in cementing the layers, and a timing mechanism (more fully hereinafter described) is employed, actuated by the main operating mechanism for determining the 45 period of the feeding operation.

Mounted upon the supporting frame 29 in suitable standards 36 is a cutter or knife 37, pivotally connected to the standards in operative relation to the rolls by links 38 and 50, 39, as plainly shown in Fig. 7.

The main operating mechanism for driving the press and the other parts of the apparatus, with the exception of the feed, is mounted upon the support 29, the several 55 shafts forming parts of the operating mechanism being journaled in suitable bearings on said support. This mechanism comprises a main drive shaft 40, carrying at one end a drive pulley 41, and at its opposite end a 60 fixed gear 42.

43 is a countershaft carrying connected gears 44 and 45 loosely mounted thereon, the gear 44 meshing with the drive gear 42 on shaft 40, and a fixed gear 46.

65 47 is a driven shaft, on which is loosely

mounted connected gears 48 and 49,—the former meshing with the gear 45 on shaft 43,—a fixed gear 50 to which is secured a star-wheel 51, and a fixed gear 52 meshing with the gear 46 on shaft 43.

70 53 is a fourth shaft carrying a fixed gear wheel 54 which meshes with the gear 49 on shaft 47, a fixed segmental gear 55 adapted to mesh with and intermittently drive the gear 50 on shaft 47, and an annulus 56 fixed 75 to the segmental gear and engaging the star-wheel 51, the annulus being provided with a notch 57 in its periphery arranged opposite the segment teeth, as plainly shown in Fig. 11. In addition to the gears described, the 80 shaft 53 also carries fixed thereto a cam wheel 58 forming part of the timing mechanism previously referred to, and a cam 59 having a camway 60 formed in one of its faces.

85 The connection between the press and the operating mechanism just described is formed by a pair of vertical levers 61 fixedly secured to a transverse shaft 62, mounted in depending bearings 63 upon the press-supporting frame 64, a transverse rod 65 connecting the upper ends of said levers, and a pair of inwardly-extending rods 66 pivotally connected to the rod 65 and to the valve 7, as plainly shown in Fig. 1. One of the 90 levers 61 is provided with an extension 67 extending into operative relation to the cam 59, and provided with an extension 68 which engages the camway 60, as plainly shown in Fig. 12.

95 The drive mechanism between the knife and the main operating mechanism comprises a crank 69 upon the end of the shaft 43, a link 70 pivoted to the link 39, and a crank rod 71 connecting the crank with the 100 pivoted link 70, shown in Fig. 7.

The timing mechanism for the feed includes, in addition to the cam 58 described, a vertical bar 72, slotted longitudinally as at 73 and 74, and mounted upon the shafts 110 31 and 53, the shafts extending through the slots in the manner indicated in Fig. 13. The lower end of this bar is provided with a spring 75 attached to the floor or support of the main operating mechanism, and at its 115 upper end carries a cross bar 76 adapted to engage a pair of escapement wheels 77 fixed upon the shaft 31 upon opposite sides of the bar 72. A roller 78 projects from one side of the bar into engagement with 120 the cam 58.

125 The clutch 34, forming a connection between the driven sprocket 30 and the gear train for the rollers, comprises a section 34^a fixed to the shaft 31, provided with a facing 34^b of leather or other suitable material, a similar facing 34^c upon the sprocket 30, and a hand-wheel 34^d upon a threaded extension 34^e on the shaft 31, as plainly shown in Fig. 12. The members of the 130

clutch are always in frictional engagement, and the degree of frictional contact is determined by the hand-wheel.

The roller 16 for applying the adhesive material to the paper is driven simultaneously with the feed mechanism by means of a sprocket chain 80 engaging a sprocket wheel 81 upon one end of the roller, and a similar sprocket wheel 82 upon the end of 10 one of the feed rolls, as plainly shown in Fig. 2.

In the operation of the apparatus, motion is imparted from the main drive shaft 40, through the gears described, to the shaft 53, 15 which is continuously driven. Intermittent motion is imparted to shaft 47 through the agency of the segmental gear, and by the intermeshing gears 52 and 46 similar intermittent motion is transmitted to shaft 43, the 20 intermittently operating gears being locked during the periods of rest by means of the star-wheel and the annulus with which it engages. The intermittent rotation of shaft 43 reciprocates the knife 37, at stated intervals, the cutter operating during the operation of the press. The rotation of cam 59 intermittently operates the levers 61 connected to the valve controlling the pneumatic press, and thus allows the fluid pressure to be applied intermittently to the 30 paper or the material passing through the press. As the cam 58 rotates, it causes the bar 72 of the timing mechanism to rise and fall, thereby throwing the locking bar 76 out 35 and into engagement with the escapement 77 periodically. The clutch members, as previously set forth, being always in frictional contact, as soon as the escapement is unlocked or released the feed rolls operate 40 through the agency of the continuously driven sprocket. One of said clutch members rotates independently of the other when the escapement is locked, and the timing means for the feed is adapted to permit the 45 feed mechanism to operate subsequent to the operation of the press.

As the layers of material to be cemented together are drawn by the feed rolls into the press,—the adhesive material being previously applied intermediate the layers or plies,—the yielding pressing surface of the press platen bears against the paper with sufficient force to properly cement the plies together, and by reason of the flexibility of 55 the platen the pressure is uniformly applied to all portions of the paper within the press regardless of any irregularities in the paper that may exist; further, any likelihood of injury to the paper that might result in 60 bringing a hard surface,—such as a plate or similar appliance,—in contact therewith is prevented through the use of a flexible diaphragm; also the heated air that is preferably used in the operation of pressing, in 65 conjunction with the drier in the press bed,

thoroughly dries the cemented layers, so that as the paper passes from the feed rolls it is in condition for storing or use.

The operation of the press will be obvious from its construction, air under pressure being admitted upon the movement of the sliding valve outwardly and the air supply cut off, and the air in the press exhausted upon the reverse movement of the valve.

While I have shown as the preferable means of cementing the layers the application of air pressure, it will be understood that any fluid may be employed without in any manner departing from the spirit of my invention. I do not therefore desire to be limited to the particular mechanism shown and described, although I consider this the preferable form, especially in the production of strawboard of the character described.

What I claim as my invention is,—

1. In a multiply paper-making machine, the combination with a pneumatic press, of feed mechanism therefor, means for intermittently operating the press and feed mechanism alternately, and an intermittently actuated cut-off mechanism operating alternately with the feed mechanism.

2. In a multiply paper-making machine, the combination with a pneumatic press, of means for feeding superimposed layers of material thereto, means for applying adhesive material intermediate the layers, and mechanism for intermittently operating the press and feeding means alternately.

3. In a multiply paper-making machine, the combination with a valve-controlled pneumatic press, of feed mechanism therefor, and means for intermittently operating the feed mechanism and press valve alternately.

4. In a multiply paper-making machine, the combination with mechanism for feeding superimposed layers of material, of means for applying adhesive material intermediate the layers, mechanism for applying fluid pressure to the coated layers, and actuating means for intermittently operating the feed and pressure-applying mechanism alternately.

5. In a multiply paper-making machine, the combination with a press, of feed rolls associated therewith, a cutter adjoining the rolls, driving means for the rolls, and a clutch connection therebetween, mechanism for intermittently operating the press and cutter simultaneously, and timing means operated by the press-actuating mechanism for controlling the operation of the clutch.

6. In a multiply paper-making machine, a press consisting of a bed and a platen having a flexible pressing surface.

7. In a multiply paper-making machine, a press comprising a bed, a platen having a flexible pressing surface, and means for applying fluid pressure to said surface.

8. In a multiply paper-making machine, a press comprising a bed, a platen having a flexible pressing surface, and means for applying elastic fluid pressure to said surface.
9. In a multiply paper-making machine, a pneumatic press comprising a bed, a platen having a flexible pressing surface, and means for applying air under pressure to said surface.
10. In a multiply paper-making machine, a press comprising a bed, a platen having a flexible diaphragm forming its pressing surface, and means for applying fluid pressure to the diaphragm.
11. In a multiply paper-making machine, a press comprising a bed, a platen in the form of a casing having a flexible diaphragm forming its bottom and the pressing surface, an air conduit communicating with said casing, and a valve controlling the discharge of air through the conduit.
12. In a multiply sheet-forming apparatus, a press, comprising a bed, a platen consisting of an inclosing casing having a flexible wall extending in operative relation to the bed, a fluid supply, and means for alternately admitting the fluid within and discharging the same from the casing.
13. In multiply sheet-forming apparatus, a press, comprising a bed, an inclosing casing thereabove having an inlet and exhaust passage, and a flexible section adjoining the bed, a fluid supply conduit having communication with the casing through its inlet, and a valve controlling the admission of the fluid within and its discharge from the casing, for the purpose set forth.
14. In multiply sheet-forming apparatus,
- a press, comprising a bed, a platen having a flexible pressing surface adjoining the bed, and a drier operatively associated with the bed.
15. In multiply sheet-forming apparatus, a press, comprising a hollow bed, a platen having a flexible pressing surface in operative relation to the bed, and a heater within the bed.
16. In multiply sheet-forming apparatus, a press, comprising a bed, an inclosing casing mounted upon and secured to the bed and having a flexible bottom section, a conduit communicating with the interior of the casing and provided with an exhaust opening, and a valve controlling the discharge through and the exhaust from the conduit.
17. In apparatus for forming multiply material, the combination with a multiple of sheet holders, of a feed mechanism adapted to deliver the sheets from the holders in superimposed relation, and means for subjecting the superimposed sheets to fluid pressure.
18. In apparatus for forming multiply material, the combination with a pneumatic press, of feed mechanism for delivering superimposed sheets of material thereto, means for applying adhesive material to the sheets prior to the operation of pressing, and means for cutting the multiply material into the desired lengths.
